UNITED STATES PATENT OFFICE.

ROBERT M. SANDERSON, OF AKRON, AND CHAUNCY P. WHISLER, OF KENMORE, OHIO.

INNER PAD FOR SHOES.

1,106,114.

Specification of Letters Patent.

Patented Aug. 4, 1914.

Application filed July 14, 1913. Serial No. 778,954.

To all whom it may concern:

Be it known that we, ROBERT M. SANDERSON and CHAUNCY P. WHISLER, citizens of the United States, residing at Akron and Kenmore, respectively, both in the county of Summit and State of Ohio, have invented new and useful Improvements in Inner Pads for Shoes, of which the following is a specification.

10 This invention relates to inner pads adapted to be inserted in the heel portions of foot-wear.

The object of the invention is to provide a pad which will afford a yielding elastic support for the heel of the wearer without producing the slightest discomfort by reason of its insertion in foot-wear as ordinarily constructed.

More especially, the invention contemplates a pad shaped to fit within the heel portion of the foot-wear provided with a shallow concave depression in the upper face of the pad at the point which receives the heel of the wearer, the marginal edge of the 25 pad surrounding the concave portion being outwardly flared or inclined to engage the wall of the heel of the shoe at its upper portion and thereby close the space between the pad and the wall effectually against the entrance of foreign substance and form a snug 30 union therewith to prevent the formation of an opening, the edges of which would tend to irritate the foot of the wearer.

A still further object of the invention is 35 to provide in the concave portion which receives the heel of the wearer a hump or slight projection which supports the central portions of the heel and the os calcis bone so that the nerves connecting with these bones 40 are less injuriously affected by the jarring incident to walking on the hard pavements, the recessed portions of the pad around the hump constituting a cushioning receptacle for this purpose.

45 With the foregoing and other objects in view, the invention consists in the novel construction, combination and arrangement of parts constituting the invention to be hereinafter specifically described and illustrated 50 in the accompanying drawings which form a part hereof wherein is shown the preferred embodiment of the invention, but it is to be understood that changes, variations and modifications can be resorted to which come 55 within the scope of the matter hereinafter claimed.

In the drawings in which similar reference numerals indicate like parts in the different figures, Figure 1, is a longitudinal view of a portion of a boot or shoe with the pad therein; Fig. 2, is a plan view of the pad; Fig. 3, is a sectional view taken on line IX of Fig. 2; and, Fig. 4, is a view taken on line X of Fig. 2.

The pad will ordinarily be constructed of 65 soft vulcanized rubber and embodies a main body portion 1 tapering from rear to front with the thin portion 2 under the arch of the foot and with the rear thickened portion 3 arranged at the heel portion of the boot or 70 shoe.

The pad is provided with a marginal edge 4 preferably outwardly inclined at 5 so as to form a slight lip at 6 extending entirely around the pad to engage the inner face of 75 the wall of the shoe especially when pressure is placed on the pad during its use, that is to say, when the weight of the wearer of the pad rests thereon the tendency is to force the marginal flange 4 laterally against 80 the wall of the shoe to prevent the formation of an opening into which portions of the flesh might enter to thereby irritate and injure the foot.

Within the marginal edge 4 is a shallow 85 concave depression 7 which constitutes a receptacle for the heel of the foot of the wearer, and preferably arranged centrally thereof is a hump or projection 8 preferably arranged so as to lie under the position normally occupied by the os calcis bone of the human foot and serve as a support therefor, in doing which the concave receptacle 7 is interrupted at this point and surrounds this hump in a horse-shoe-shaped fashion. The 90 upper surface of the pad is preferably covered with a layer 9 of fabric to assist the cushioning effect, prevent wear on the hosiery used, and also to act as an insulating medium between the foot of the wearer and 100 the rubber of the pad.

The under face of the pad is arranged to fit the normally-constructed foot-wear of commerce and the upper face of the pad is fashioned to approximate as nearly as possible the actual shape and contour of the under face of the heel of the average human foot with the projection 8 arranged in such a position as to support those portions of the heel of the wearer which are unsupported by the ordinary foot-wear and thereby relieve the foot from strain and support 105 110

the os calcis bone from the jar and shock, thereby relieving the nerves connected with this bone from strain which should ordinarily be present were the central portion of 5 the heel of the wearer unsupported.

We claim:

1. In a device of the character described, a pad body having a lower flat face and lateral faces fashioned to fit within the heel! 10 portion of a boot or shoe and having an upper face containing a semi-circularly formed depression located in the heel portion of the pad constituting a seat for the marginal portion of the heel of the wearer, 15 and provided with a hump or projection formed by an excess of material arranged approximately centrally of said depression and constituting means for supporting what would otherwise be an unsupported portion 20 of the heel of the wearer.
2. In a device of the character described, a pad body having a lower flat face and lateral faces fashioned to fit within the heel portion of a boot or shoe and having an 25 upper face containing a semi-circular depression constituting a receptacle for the

heel of the wearer and further provided with a hump or projection formed by an excess of material positioned centrally of said depression so as to lie approximately under the 30 heel bones of the normal human foot.

3. In a device of the character described, a pad body fashioned to fit within the heel portion of a boot or shoe and having a lateral face upwardly and outwardly-inclined, 35 said pad further provided with a semi-circular depression in its upper face comprising a receptacle for the heel of the wearer and a hump or projection formed by an excess of material arranged approximately 40 centrally of said depression and adjacent the rear end thereof and constituting means for normally supporting the unsupported portion of the heel of the wearer.

In testimony whereof we have hereunto 45 set our hands in presence of two subscribing witnesses.

ROBERT M. SANDERSON.
CHAUNCY P. WHISLER.
